MOP HEAD HOOD

W. Revard Auwarter, Memphis, Tenn., assignor to
Gem, Incorporated, Byhalia, Miss., a corporation
of Mississippi

Filed May 27, 1963, Ser. No. 75,076

Term of patent 14 years

(Cl. D9—2)

FIGURE 1 is a perspective view illustrating the mop head hood of the present invention.

FIGURE 2 is a top plan view thereof.

FIGURE 3 is an enlarged elevational view of one end thereof.

FIGURE 4 is an enlarged elevational view of the other end thereof.

FIGURE 5 is an enlarged side elevational view.

FIGURE 6 is an enlarged bottom plan view thereof.

The side not shown is a mirror image of the side shown in FIGURE 5.

The dotted line showing of a mop handle and mop head in FIGURE 1 is for illustrative purposes only.

I claim:

The ornamental design for a mop head hood, as shown and described.
